ADJUSTABLE SUPPORT FOR CEILING LIGHTING FIXTURES

Vincent Esoldi, Stirling, N. J.

Application March 29, 1950, Serial No. 152,657

6 Claims. (Cl. 248—216)

1

This invention relates to adjustable supports for supporting ceiling lighting fixtures and while particularly adaptable for such service has many other uses, among which are supports between the open beams of a house basement to provide for the supported storage of various objects between the beams, or as supports for hooks from which articles may be hung, etc.

An object of the invention is to provide a support adjustable as to length which may be conveniently and easily affixed between two ceiling beams or analogous elements, to provide a firm, rigid support on or from which lighting fixtures or other objects may be supported, and one which will greatly facilitate the hanging of lighting fixtures in a house already built, as well as saving labor and promoting the convenience of such installations in new building construction.

With these and other objects in view, as may appear from the accompanying specification, the invention consists of various features of construction and combination of parts, which will be first described in connection with the accompanying drawings, showing an adjustable support for ceiling lighting fixtures of a preferred form embodying the invention, and the features forming the invention will be specifically pointed out in the claims.

In the drawings:

Figure 1 is a top plan of the improved support.

Figure 2 is a side elevation of the support.

Figure 3 is a vertical section through the support taken on the line 3—3 of Figure 2.

Figure 4 is a fragmentary perspective view illustrating the manner of attaching the support.

Figure 5 is a detailed cross-section taken on the line 5—5 of Figure 3.

Figure 6 is a perspective view of a supporting clamp or strap employed in the support structure.

Figure 7 is a top plan of a connecting strap employed in the support structure.

Figure 8 is an end elevation of the connecting strap shown in Figure 7 of the drawings.

Figure 9 is a top plan of a modified form of the invention.

Figure 10 is a side elevation of the modified form of the invention.

Figure 11 is a fragmentary plan view of the modified form of the invention.

Figure 12 is a top plan of a modified form of the holding strap.

Figure 13 is a section on the line 13—13 of Figure 12.

Referring more particularly to the drawings, 55

2

the main body 1 of the adjustable support is composed of a pair of channel members 2 and 3 each of which are similar in construction so that only one die may be required for stamping both channel members, thus reducing the cost of their manufacture. Each of the channel members 2 and 3 has angled sides 4 and 5 so that the two channel members will nest each with one of its sides engaging the exterior of the side of the other as shown in Figure 3 of the drawings, thus providing an elongated supporting member.

The bases of the channel members 2 and 3 are provided with a plurality of longitudinally spaced laterally extending slots 6 which are provided for the purpose of facilitating the adjustment of the length of the support and its attachment to ceiling beams, studs or like structures. The two channel members 2 and 3 are held in slidable engagement with each other by straps 7 which extend across and are carried by one of the channel members and have ears 8 which overlap the other channel member so as to permit longitudinal movement of the channel members relative to each other but prevent independent lateral movement of the channel members. The straps 7 have depending tongues 9 cut therefrom which extend into the endmost slots 6 on one of the channel members as clearly shown in Figures 1 and 4 of the drawings.

30 A supporting strap 10 is adjustably mounted upon the channel members to slide therealong and it has laterally extending ears 11 which engage over the upper base of the channel members 3 so as to support the supporting strap 10 upon the channel members. The supporting strap 10 has a depending offset portion 12 which threadably carries a stud 13.

Each of the bases of the channel members 2 and 3 has a pointed projection 14 on its end 40 which is sharpened to form a knife edge as shown at 15 and in mounting the support its length is extended so that these points will engage the ceiling beams, stud or the like, indicated at A in Figures 1 and 4 of the drawings, after which a screw driver or other similar tool, indicated at 13', is inserted through two of the slots in the bases and by applying a prying action on the tool B the two channel members will be forced longitudinally in opposite directions, forcing the 45 knife-edged points 14 into the wood of the beams, studs or the like for securely attaching the support. When the support is used to support a ceiling lighting fixture, a ceiling box 16 of the usual type is attached to the adjustable supporting strap 10 by means of a fixture stud 17. The fix-

ture stud 17 is of the usual type which may be purchased upon the open market except that it has a slot 18 cut therein its full length and into its center so that it may be slipped laterally over the stud 13 permitting the stud to be threaded into the supporting strap 10. While the fixture stud is applied by tightening the stud 13, the fixture stud 17 and the ceiling box 16 will be tightly clamped against the supporting strap 10 and this strap, being of metal will be clamped against the channel members 2 and 3 forming a firm, rigid support for the ceiling box 16, as well as a lighting fixture (not shown) which is attached by means of the fixture stud 17. These fixture studs are externally threaded so as to permit the attachment of a lighting fixture thereto. The tightening of the screw 13 will also cause the strap 10 to tightly clamp the channel members 2 and 3 in adjusted positions.

The support is particularly adaptable and advantageous in putting ceiling fixtures in the ceilings of buildings already made in that all that is necessary is to cut a hole in the ceiling the size of the ceiling box 16 then by tilting the support, before the ceiling box is applied, it is inserted through this relatively small opening, placed in a level horizontal position and by means of screw driver or tool B the knife-edged points 15 are forced into two of the ceiling beams securely attaching the support. After the support has been attached to the ceiling beams the ceiling box 16 is placed in position with the projecting portion 12 of the supporting strap 10 extending through the opening 20 which is standard in the base of the ceiling box. The fixture stud is then moved laterally over the threaded stud 13 and the latter is tightened to securely connect the ceiling box and the fixture stud to the support.

The support is equally useful in new building construction in that it may be quickly and easily attached between two ceiling studs and adjusted to accommodate the distance between the studs without requiring any sawing or cutting of the support, and it also may be used between various other wooden supports such as studs in an unfinished room to provide means for attaching hooks or the like from which articles may be suspended, as well as being adaptable for placing between ceiling beams of an unfinished room to provide supports for storage of material between the beams and out of the way.

The modified form of the invention shown in Figures 9 to 11 of the drawings is similar in all major respects to the form of the invention shown in Figures 1 to 6, inclusive, in that it comprises a pair of identical channel members 30 and 31 nested so that the base 32 of one of the members is spaced from the corresponding base 32 of the other member, as is clearly shown in Figures 4 and 10 of the drawings.

In the modified form of the invention the channel members 30 and 31 have the pointed inserting elements 33 formed on their ends which correspond to the pointed or sharpened projections 14. The channel members 30 and 31 are also provided with longitudinally spaced laterally extending slots 34' corresponding to the slots 6 by means of which the two channel members may be adjusted longitudinally relative to each other to force the pointed inserting projections 33 into the beams indicated at A of a building construction. Connecting guiding straps 34 are mounted about the channel members 30 and 31 and correspond to the straps 7. Two of these straps 34 are shown in the drawings, but it is to be understood

that only one such strap may be employed, if desired. The straps 34 are similar to the straps 7, differing therefrom in that the straps 34 have projections 35 struck therefrom which engage in detent fashion in any one of the slots 34' to hold the straps against movement relative to one or the other of the channel members depending upon the channel member provided with the slot in which the projection engages.

In the modification of the invention shown in Figures 9 to 11, spacing tongues 38 are cut from the bases of each of the channel members near their ends provided with the pointed inserting elements 33, and when it is desired to attach the adjustable supporting structure to wooden beams in a building the spacing tongues 38 are bent at right angles to the bases 32 and cut by tin shears or the like to the desired proper length for temporarily supporting the adjustable support at the proper distance above a ceiling, indicated at B through which a switch box 39 is to be suspended, and thus the adjustable support will be supported at the proper elevation during the prying apart of the two channel members by a prying tool such as indicated at 13' in Figure 4 of the drawings. The fixture or switch box 39 is supported from the adjustably connected channel members 30 and 31 by a strap 40 in the same manner in which the switch or fixture box 16 is supported from the adjustable channel members 2 and 3 of the form of the invention shown in Figures 1 to 5 of the drawings.

It will be understood that the invention is not to be limited to the specific construction or arrangement of parts shown, but that they may be widely modified within the invention defined by the claims.

What is claimed is:

1. An adjustable support comprising a pair of nested channel members, means holding said members in slidable engagement for longitudinal adjustment relative to each other, a pointed knife-edged inserting member formed on one end of each of said channel members and disposed in opposed relation at opposite ends of the support, the bases of said channel members which form the top and bottom of the support provided with a plurality of laterally extending longitudinally spaced slots to receive a prying tool to provide relative longitudinal adjustment of the channel members and to force said inserting members into wooden house beams, a supporting strap slidably carried by said channel members, a threaded stud threadably connected to said supporting strap, and a fixture stud removably engaged by the head of said threaded stud, said fixture stud having a portion thereof cut away so that it may be moved laterally over the threaded stud when the latter is connected to said supporting strap, said holding means having tongues cut therefrom which extend into certain of said slots to rigidly connect the holding means to the channel members.

2. An adjustable support as claimed in claim 1 wherein said bases have spacing tongues cut therefrom near their ends, said tongues adjustable to fixed lengths and adapted to be bent at right angles to said bases to form temporary spacing supports for the adjustable support during its attachment to building beams.

3. An adjustable support comprising a pair of nested channel members, a pointed knife edge inserting member formed on one end of each of said channel members and disposed in opposed relation at opposite ends of the support, the bases

of said channel members which form the top and bottom of the support provided with a plurality of laterally extending longitudinally spaced slots to receive a prying tool for longitudinally adjusting the channel members relative to each other to force said inserting members in opposite directions, spaced holding members about said channel members to hold them in sliding engagement, each of said holding members having a projection thereon, the projection of one of said holding members adapted to engage at least one of the slots on the base of one of said channel members and the projection on the other holding means adapted to engage at least one of the slots on the base of the other channel member 15 to prevent movement of each of said holding means relative to said channel members.

4. In an adjustable support as claimed in claim 3 wherein said projection in each of said holding means comprises a medially disposed indentation 20 to engage at least one of said slots in detent fashion.

5. In an adjustable support as claimed in claim 3 wherein said projection on each of said holding means comprises a tongue struck therefrom for 25 engagement with at least one of said slots.

6. An adjustable support as claimed in claim 3 wherein said bases have spacing tongues cut therefrom near their ends, said tongues adjustable by cutting to fixed lengths and adapted to be bent at right angles to said bases to form temporary spacing supports for the adjustable support during the attachment thereof.

VINCENT E. SOLDI.
